(57) **CLAIM**

The ornamental design for a finial for curtain pole, as shown and described.

DESCRIPTION

FIG. 1 is a front, top perspective view of the first embodiment of a finial for curtain pole, showing my new design; FIG. 2 is a rear, bottom perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view of the reduced scale thereof; and, FIG. 8 is a bottom plan view of the reduced scale thereof. The dashed broken lines in the figures are for the purposes of illustrating portions of the finial for curtain pole and form no part of the claimed design.

1 Claim, 8 Drawing Sheets
